[57] CLAIM

The ornamental design for a face mask for protection against the elements, as shown and described.

DESCRIPTION

FIG. 1 is a frontal perspective view of a face mask for protection against the elements showing my new design; FIG. 2 is a front elevational view of the face mask of FIG. 1;

FIG. 3 is a side view of the face mask of FIG. 1 viewed from the left, the right side being a mirror image of FIG. 4; FIG. 4 is a rear elevational view of the face mask shown in FIG. 1;

FIG. 5 is a top view of the face mask of FIG. 1; and,

FIG. 6 is a bottom view of the face mask of FIG. 1.

The broken lines in FIG. 5 represent conventional stitching.
